UNITED STATES PATENT OFFICE.

WILLIAM H. BLAIR, OF JANEVILLE, WISCONSIN.

PILE-DRIVER.

SPECIFICATION forming part of Letters Patent No. 433,929, dated August 12, 1890.

Application filed March 5, 1890. Serial No. 342,753. (No model.)

To all whom it may concern:

Be it known that I, WILLIAM H. BLAIR, a citizen of Janesville, in the county of Rock and State of Wisconsin, have invented certain new and useful Improvements in Pile-Drivers; and I do hereby declare the following to be a full, clear, and exact description of the invention, such as will enable others skilled in the art to which it appertains to make and use the same.

My invention relates to an improvement in machines for driving posts, piles, &c., and is designed more particularly for driving fence-posts, the object being to produce a machine for driving posts which shall be of simple construction and effective in operation.

A further object is to so construct the machine that it may be placed upon and operated from a wagon.

20 A further object is to construct a pile or post driving machine in such a manner that the uprights which carry the hammer can be adjusted relatively to the ground, so as to be maintained in a vertical position relatively thereto.

25 With these objects in view the invention consists in certain novel features of construction and combinations and arrangements of parts, as hereinafter set forth, and pointed out in the claims.

30 In the accompanying drawings, Figure 1 is a plan view of my improvement. Fig. 2 is a side view. Fig. 3 is a rear view. Figs. 4, 5, 6, 7, 8, 9, and 10 are views of certain details.

35 A A represent the side-boards of a wagon on which my improved post-driver may be supported, a recess being made in one end of each side-board for the reception of the ends of a front cross-bar B. Bolts b are passed 40 through the side-board and cross-bars B, as shown in Fig. 9, to secure these parts together. The rear cross-bar B' extends at its ends beyond the side-boards A, for a purpose hereinafter explained.

45 Comprising a portion of the base of the machine are two timbers C C, disposed at an angle to each other, as shown in Fig. 1, the rear ends of the timbers C being inserted in the angle formed by the cross-bar B' and 50 said boards A at each side of the wagon, and bolts b' are passed through the side-boards

and timbers C, and other bolts b² are passed through the ends of the timbers C and cross-bar B', as shown in Fig. 7. The forward ends of the timbers C extend beyond the 55 cross-bar B, and are secured to said cross-bar by means of suitable bolts. At or near the free ends of the timbers C said timbers are made convex on their inner faces, and to these convex ends of the timbers C two parallel 60 uprights D are bolted by means of bolts x, the holes through which said bolts pass being made sufficiently large, as shown in Fig. 10, to permit the uprights D to be capable of an oscillating movement on the bolts x, and 65 countersinks y are preferably made in the outer faces of the uprights D for the reception of the heads of the bolts x. The uprights are pivotally connected together at their ends by means of a cross-bar E, having 70 slots in its ends to receive the ends of the uprights, said slots having convex walls at their inner ends, as shown in dotted lines in Fig. 3, so that the uprights may turn on their 75 pivotal connection with the cross-bar.

Connected by means of double hinges to the uprights D D are brace-timbers F F', the brace F' being hinged at a higher point than the brace F, so that said braces may be crossed, as shown in Fig. 3, without conflict with each 80 other.

The hinges F², by means of which the braces are connected to the uprights, are preferably made so that they will be capable of turning in either direction. A simple manner of making such hinges is shown in Fig. 5. A piece of any suitable metal is provided at one end with a loop or opening c and secured to each brace F F'. The other leaf of the hinge is provided with a pintle c' to enter the loop c, and may be pivotally connected to the uprights D D by means of suitable bolts d, upon which the braces are capable of swinging, washers d' being secured between the hinge and the upright to protect the up-right from abrasion by the action of the double hinge, which is either on the pintle c' or on bolt d. The brace-timbers F F' are crossed, as above explained, and attached at or near their lower ends to the ends of the 90 rear cross-bar B' through the medium of weighted arms G and brackets H. The

weighted arms G are provided at or near one end with loops G', through which the brace-timbers F F' are adapted to pass, the weighted ends G² of the arms projecting at an angle 5 from the timbers F F', and thus serve to clamp or grip said timbers in the loops G'.

Projecting from the rear end of each arm G is a flange or ear H', having a curved outer face H², a bolt-hole H³, and a countersunk 10 portion H⁴ for the reception of the head of a bolt I. By means of these bolts each weighted arm is secured to the flange J of a bracket H, secured at the ends of the cross-bar B'. The flange J is preferably curved in a direction 15 opposite to the curvature of the outer face of the flange H' of arm G. The object in constructing the flanges H J and connecting them together, as above set forth, is to permit the frame to swing when it is being adjusted to 20 the desired angle relatively to the ground, and at the same time produce a firm connection of the parts.

Located in the space between the uprights D is a weight K, having grooved flanges K', 25 adapted to loosely embrace the uprights. A sheaf L is suspended from the cross-bar E and provided with pulleys M. A rope or chain N is passed over these pulleys and attached to the weight K. Thus a drop-hammer is 30 produced, and is operated in the usual manner.

Assuming now that it is desired to drive a post on a hillside, the uprights D D are made to assume a vertical position relatively 35 to the ground, the brace-timbers F F' being permitted to slide freely through the loops G', on arms G. When the uprights are in the desired positions, the weighted arms will cause the brace-timbers F F' to be gripped or 40 clamped in the loops or collars G', and the uprights will be maintained in the desired position. Thus it will be seen that the weighted arms and loops or collars produce in effect weighted clamps, which are automatic in their operation. The uprights having 45 been secured in a vertical position, as above explained, a post is inserted between them, as shown in Fig. 3, and the drop-hammer operated in the usual manner, to drive 50 it into the ground.

It is of course to be understood that my improved machine may be mounted on a set of wheels, instead of upon a wagon, as above explained, or it may be mounted in any other preferred manner.

Having fully described my invention, what I claim as new, and desire to secure by Letters Patent, is—

1. In a pile-driver, the combination, with a base-frame, of parallel uprights pivotally attached thereto, brace-timbers connected at their upper ends to the uprights by means of double hinges, said brace-timbers being adjustably connected at their lower ends to the base-frame, and a drop-hammer, substantially as set forth. 65

2. In a pile-driver, the combination, with a base-frame, of parallel uprights adjustably attached thereto, brace-timbers hinged at their upper ends to the uprights, weighted clamping devices adjustably attached to the brace-timbers and secured to the base-frame, and a drop-hammer, substantially as set forth. 70

3. In a pile-driver, the combination, with the base-frame, of parallel uprights adjustably attached thereto, brace-timbers hinged to the uprights, weighted arms having loops through which the brace-timbers pass, and a flange on said weighted arms, said flanges being secured to the base-frame, substantially as set forth. 75

4. In a pile-driver, the combination, with a base-frame, of parallel uprights adjustably attached thereto, brace-timbers hinged at their upper ends to the uprights, weighted arms having loops through which the brace-timbers 85 pass, a flange having a curved face projecting from the weighted arm, a bracket having a curved flange secured to the base-frame, said flanges being secured together, and a drop-hammer, substantially as set forth. 90

In testimony whereof I have signed this specification in the presence of two subscribing witnesses.

WILLIAM H. BLAIR.
